NECK WEIGHT RELIEVING HARNESS ATTACHMENT

Filed June 5, 1924

Inventor
Homer T. Jones

UNITED STATES PATENT OFFICE.

HOMER T. JONES, OF ORD, NEBRASKA.

NECK-WEIGHT-RELIEVING HARNESS ATTACHMENT.

Application filed June 5, 1924. Serial No. 718,016.

To all whom it may concern:

Be it known that I, HOMER T. JONES, a citizen of the United States, residing at Ord, in the county of Valley and the State 5 of Nebraska, have invented a new and useful Neck-Weight-Relieving Harness Attachment, of which the following is a specification.

The invention relates to improvements in a neck weight relieving harness attachment 10 in which a flexible web hanging on the withers of the horse supports the traces at a place above the normal; and the objects of the improvement are: first, to provide a means of supporting the traces in a manner to make the course of tension come more horizontally from the collar, and so adapted 15 that the horse can carry it without unnecessary effort, also placed where it is the least apt to cause sores;—second, to provide a means of relieving the weight on the horse's 20 neck by removing the cause of the weight as much as possible; third, to provide a neck weight relieving harness attachment that is durable, light and convenient and 25 is not tiresome for the horse to carry.

One form of the invention is illustrated in the accompanying drawing, in which Fig. 1 shows where it hangs on the horse and the method of connecting it to the harness. 30 The harness being illustrated with the dotted lines.

Fig. 2 is a detailed view of the means of connection to the traces, the flexible web being removed.

Referring to Fig. 1, to each end of the web 1 is attached a loop 2, holding the fastener 3, the adjusting strap 4 is attached to and looped through a loop 5, then passed through and under the clutch 6.

It can be seen that the hammock shaped web 1, hangs comfortably on the withers of the horse, the strap 7 being tied to the upper hame strap of the harness holds the web from creeping backward when the horse 40 is in motion, it also guides the said web into place when the harness is being placed on the horse.

Attached to each end of the web 1, is a web loop 2, making connection to the fastener 3, the frame of this fastener is constructed from a rod with each end bent up then out and looped behind as illustrated in Fig. 2.

Around the vertical bars of the fastener is moveable thereon a clutch 6, with an opening 8 to receive the adjusting strap 4, the end of the strap is then passed under the clutch as shown, thus when tension is applied the clutch retains the strap.

To one end of the said adjusting strap 60 is attached a loop 5, the strap is then looped through it, this loop renders it possible to make connections to the traces at any desired place. When the traces are raised as illustrated in Fig. 1 it will be seen that the 65 collar by the motion of the horse is forced to creep upwards.

It will also be seen from the foregoing description that there is little danger of 70 this attachment causing sores at this point of the horse as the adjusting straps, fasteners and the web all reciprocate with the scapula of the horse.

It will also be seen that there is little 75 liability of it getting caught on a foreign object, and it will be noticed that it is light and convenient being connected to the harness in three places it causes very little inconvenience while handling the harness.

I claim:

A neck weight relieving attachment comprising a flexible web adapted to hang over the withers of a horse, tucked portions on the ends of said web forming cup shaped hangers, fasteners attached to the ends of said web having offset portions engaging in the cup portions of the web and vertical side bars, strap retaining members slideable on said bars, straps retained by said retaining members, and means on said straps for 85 engaging with the traces of the harness. 90

HOMER T. JONES.
